HANS VON REPPERT, OF COLOGNE, GERMANY.

MECHANICAL BELL-RINGING DEVICE.

1,124,525.

Specification of Letters Patent. Patented Jan. 12, 1915.

Application filed December 23, 1913. Serial No. 808,380.

To all whom it may concern:

Be it known that I, HANS VON REPPERT, a subject of the German Emperor, residing at Cologne, Germany, have invented new and useful Improvements in Mechanical Bell-Ringing Devices, of which the following is a specification.

This invention relates to a bell ringing device driven by an electric motor which is coupled with the bell during each oscillation only for a determined fraction of the oscillation of the bell.

The invention is characterized by the following arrangement. Arranged on the motor shaft is a stationary and an auxiliary movable friction wheel connected to the axis of the bell by an endless pulling medium and adapted to be thrown in and out by means of centrifugal weights. Moreover actuated from the axis of the bell by means of a second pulling medium is a switch arrangement by means of which a circuit is closed at appropriate moments or reversed.

The improved bell ringing device is illustrated in the accompanying drawing in Figure 1 in a front view, and in Fig. 2 in a lateral view. Fig. 3 shows on a reduced scale the amplitude of oscillation and Fig. 4 represents the switch and circuit arrangement.

Arranged on the shaft *b* of the motor *a* is a friction clutch *c*, *c'* constituted by two conical friction wheels of which the wheel *c* is fast on the shaft and the wheel *c'* axially movable thereon. This latter wheel by means of an endless chain *e* is connected with the axis or rocking shaft *f* of the bell *g*.

d are centrifugal weights by the movement of which the movable friction wheel is pressed against the stationary friction wheel by means of the rods *d'*. During the oscillation of the bell *g* moreover a shaft *i* is actuated through the agency of an endless cord *h*, this shaft carrying two contact members or arms *k*, *k'*. These contact arms as shown particularly in Fig. 2 are adapted to move between two members *u*, *v* and *u'*, *v'* respectively arranged on loose contact disks *l* and *l'*. Each of these contact disks has its circumference composed of a non-conductive segment *n* or *n'* and of two separate contact rails *p*, *q* or *p'* and *q'* separated by an insulating member *o* and *o'* respectively. Adapted to wipe along these contact members are brushes *r*, *r'*. In the present in-

stance use is made of a three-phase motor. According to Fig. 4, of the three conductors *s'*, *s²*, *s³* the conductor *s'* is directly connected to one pole *t'* of the motor. In this circuit arrangement and for the purpose of clearness the two contact disks *l* and *l'* are shown superposed although they are loosely arranged on the same shaft *i*. The other two conductors *s²* and *s³* are attached to the contact arms *k*, *k'*.

In accordance with Fig. 3 the bell is to move commencing from one end of its amplitude 1, first along the arc portion 1 and 2 freely, then along the arc portion 2, 3, 70 that is to say, to about the center of its amplitude by means of the motor and ultimately should continue freely to complete the remaining arc portion 3, 4 in upward direction. In this oscillation of the bell the contact arms *k* and *k'* by means of the endless rope *h* are rotated in the same direction as indicated by the arrows shown whereby the said arms are brought into contact with the members *u* and *u'*. Consequently a circuit is closed through the following path. *s'* being attached directly to the pole *t'* of the motor current flows through *s²* contact arm *k*, member *u* conductor *w* contact rail *p* brush *r* to the second pole *t²* of the motor. 80 In a similar manner current flows from the conductor *s³* to the third pole *t³*. The motor therefore is supplied with current during the downward movement of the bell. It is accelerated and on reaching a certain speed the centrifugal weights *d* throw the friction clutch *c*, *c'* into action at the point 2 of the bell movement. The latter therefore is now driven along the arc 2, 3. When the bell passes the center position the contact disks *l*, *l'* carried along by the contact arms *k*, *k'* assume approximately the central position shown in Fig. 4 and in the further oscillating movement the contact rods *q* and *q'* are brought under the brushes in the place of the contact rails *p* and *p'*. The circuit is thus immediately broken and the bell oscillates along the arc 3, 4 freely in upward direction in which action the centrifugal weights are caused to release the friction clutch. 95

As soon as the bell resumes its downward oscillation from the reversing point 4 the contact arms *k* and *k'* are brought into engagement with the members *v*, *v'* respectively, thereby effecting a reversal in the conductors *s²*, and *s³* with the result that the

current now flows in the following manner: The current in s^2 flows through the contact arms k , contact v , conductor x , contact rail q' and brush r' to pole t^3 of the motor. In 5 a similar manner the current flows from the conductor s^3 through contact arm k' , member v' , conductor x' , contact rail q and brush r which now rests on q of the pole t^2 of the motor. The latter therefore is reversed and 10 is rotated in the opposite direction. As soon as it has reached a certain acceleration the centrifugal weights are caused to throw the friction clutch into action and the bell receives its drive down to the center of its os- 15 cillation, at which point the contact rails p again take the place of the contact rails q with regard to the wiping brushes. The current therefore is interrupted and the bell is caused freely to move in an upward di- 20 rection to the initial point 1, after which the same play is again repeated. Prior to the commencement of the oscillation the contact arms are fairly in the center between the members v and u and v' and u' respec- 25 tively and therefore would produce no contact. In order however to enable, at the outset a mechanical commencement of the ringing to take place without manual assistance a resilient contact y is arranged 30 on the contact member u and a similar contact y' on the contact member u' and moreover the contact brushes r r' are slightly unsymmetrical with regard to the initial position of the contact disks so as, 35 to be in contact with the contact rails p p' . Immediately upon switching on current the motor therefore is driven causing the bell mechanically to commence its movements which gradually increase to their normal 40 amplitude. In this way therefore an entirely mechanical operation is rendered possible both for initially ringing or starting the bell as well as for its normal oscillations. 45 What I claim and desire to secure by Letters Patent is:—

1. A mechanical bell ringing device comprising, in combination, a motor, an oscillating bell, means for connecting the bell in- 50 termittently with the motor to cause motive impulses to be imparted to the former throughout a predetermined portion of each

oscillation, an electric circuit for the motor, a switch device consisting of a rocking shaft, contact arms mounted fixedly upon 55 the shaft, a pulling medium connecting the said shaft with the bell for oscillation there- with, loose contact disks mounted upon the last-named shaft, engaging members ar- ranged upon each of said disks and between 60 which the adjacent contact arm may oscil- late, a pair of insulated contact rails ar- ranged upon each contact disk, and contact brushes connected in the motor circuit and being mounted to wipe the contact rails of 65 the respective disks.

2. A mechanical bell ringing device comprising, in combination, a motor, an oscillating bell, means for connecting the bell in- 70 termittently with the motor to cause motive impulses to be imparted to the former throughout a predetermined portion of each oscillation, an electric circuit for the motor, a switch device consisting of a rocking shaft, contact arms mounted fixedly upon 75 the shaft, a pulling medium connecting the said shaft with the bell for oscillation there- with, loose contact disks mounted upon the last-named shaft, engaging members ar- ranged upon each of said disks and between 80 which the adjacent contact arm may oscil- late, a pair of insulated contact rails ar- ranged upon each contact disk, contact brushes connected in the motor circuit and being mounted to wipe the contact rails of 85 the respective disks, and a spring contact mounted upon one of the engaging mem- bers of each contact disk inwardly thereof for engagement with the corresponding contact arm when the bell is in its initial posi- 90 tion of movement, the said contact brushes being adapted to be adjusted circumferen- tially with respect to the contact disks to render the spring contact adapted to engage the corresponding contact arms when the 95 bell is in its normal inoperative position.

In testimony whereof I have signed my name to this specification in the presence of two subscribing witnesses.

HANS von REPPERT.
